United States Patent Office.

AUGUSTUS THAYER, OF ALBANY, NEW YORK.

Letters Patent No. 77,333, dated April 28, 1868.

COMBINED SCREEN AND SHOVEL.

The Schedule referred to in these Letters Patent and making part of the same.

TO ALL WHOM IT MAY CONCERN:

Be it known that I, AUGUSTUS THAYER, of Albany, in the county of Albany, and State of New York, have invented a new and improved Combination of a Screen and Scoop; and I do hereby declare that the following is a full, clear, and exact description thereof, which will enable those skilled in the art to make and use the same, reference being had to the accompanying drawings, forming part of this specification.

This invention consists in a new and improved combination of a screen and scoop, as hereinafter fully shown and described, whereby a scoop or small shovel may, with the greatest facility, be converted into a screen whenever desired.

The invention is applicable to fire-shovels, and may be applied to scoops of all kinds.

In the accompanying sheet of drawings—

Figure 1 is a plan or top view of my invention.

Figure 2, a transverse vertical section of the same, taken in the line $x x$, fig. 1.

Similar letters of reference indicate corresponding parts.

The scoop may be constructed of sheet metal, ordinary tinned plate, or galvanized iron plate, according to the use for which the implement is designed. It is constructed with a back, a , and two sides, $b b$, the back having a handle, c , attached, of any suitable length.

The device has no permanent bottom, but at the inner surface of the lower part of each side b there are two parallel grooves, $d d$, placed one above the other, as shown clearly in fig. 2, a slide, A , being fitted in the lower grooves, and a screen, B , in the upper grooves, or *vice versa*.

The front or outer end of the scoop is provided with a flap or door, C , which is connected at its lower end, by a hinge or any suitable joint, to the scoop, and a spiral or other suitable spring, e , is applied to the flap or door, which spring, by a slight shake-motion of the scoop, has a tendency to throw the flap or door up, and keep the end of the scoop closed, said flap or door opening inward or backward by a very slight pressure, the door, when elevated and closed, bearing against stops f , at the inner surfaces of the sides $b b$.

When the device is used as a scoop, the screen B may be withdrawn, and when used as a screen the slide A is withdrawn.

In shoveling the front end of the device into the article to be lifted and screened, the flap or door C will be forced back, and the screen will be filled, and, by a slight shake of the device, the flap or door will be raised by the spring e , and the substance may then be screened by shaking the device.

When the substance is fully screened, the fine portion having passed through the screen, the coarser particles left on the top, may be discharged by shoveling back the flap or door, or by simply inverting the implement.

This device may be very cheaply constructed, and used for fire-shovels, for sifting cinders from shovels, and also for scoops generally.

Different-sized screens may be used, according to the character or nature of the material to be screened.

I claim as new, and desire to secure by Letters Patent—

1. A combined scoop and screen, provided with a removable bottom or slide, and a removable or sliding screen, arranged in the manner substantially as shown and described.

2. The flap or door C , arranged with a spring to operate in the manner substantially as and for the purpose specified.

3. The combination of the screen and removable bottom with the flap or door C , all constructed, arranged, and applied to operate in the manner substantially as and for the purpose set forth.

AUGUSTUS THAYER.
